UNITED STATES PATENT OFFICE

154,406

DESIGN FOR A SLED RUNNER FOR
WHEELED VEHICLES

Frank F. Mattmann, Cliffside Park, N. J.

Application January 13, 1948, Serial No. 143,718

Term of patent 7 years

(Cl. D14—24)

To all whom it may concern:

Be it known that I, Frank F. Mattmann, a citizen of the United States and resident of Cliffside Park, in the county of Bergen and State of New Jersey, have invented certain new, original, and ornamental Design for Sled Runner for Wheeled Vehicles, of which the following is a specification, reference being had to the accompanying drawing, forming part thereof.

Fig. 1 is a perspective view of a sled runner for wheeled vehicles embodying the invention;

Figure 2 is a top plan view of the sled runner for wheeled vehicles shown in Fig. 1, with its attaching member shown mounted thereon in dotted lines for illustration purposes only; and

Figure 3 is a side elevational view of the sled runner for wheeled vehicles shown in Figure 2, with its attaching members shown mounted

thereon in dotted lines for illustration purposes only.

What I claim is:

The ornamental design for a sled runner for wheeled vehicles, substantially as shown and described.

FRANK F. MATTMANN.
